INVENTOR

Frank M. Ashley

UNITED STATES PATENT OFFICE

FRANK M. ASHLEY, OF BROOKLYN, NEW YORK

PIPE FOR SMOKING TOBACCO

Application filed June 15, 1927. Serial No. 198,946.

My invention relates to pipes for smoking tobacco.

The object of my invention is to provide a pipe for use with a filter which is located in the stem of the pipe and held in the mouthpiece portion and is removable therewith from the stem and bowl portion.

A further object is to provide a pipe having a chamber formed between the stem and inner end of the mouthpiece to collect any juices which may flow from the bowl to said chamber which may not have been absorbed by said absorbent material.

A further object is to provide a stem portion having a continuous duct therethru from end to end which may be easily cleaned by the insertion of the ordinary pipe cleaner.

Further objects and advantages of my invention will be hereinafter set forth:

Referring to the drawings which form a part of this specification—

Fig. 1 is a longitudinal sectional view of a pipe embodying my invention.

Fig. 2 is a longitudinal view of a portion 25 of the stem of the pipe shown partly in section, together with the filter held thereby, both shown on an enlarged scale.

A, indicates a bowl having a stem A¹ preferable formed integral therewith substantially as shown and having a chamber A² for tobacco. B, indicates a mouthpiece which is provided with a reduced portion B¹ at its inner end which fits in the bore C. A bore C¹ of reduced diameter relative to the bore C communicates with the chamber A² as illustrated.

The bore C¹ is preferably extended beyond the opening A³ in the bottom of the bowl to form a recess A⁴ into which the free end of the filtering material D may rest. The filtering material comprises a central wire portion E on which absorbent material D¹ is mounted and held in firm relation to the wire E, which

wire is flexible.

The diameter of the bore C¹ is greater than the outer diameter of the cylindrical filtering material D¹ so that should the filtering material become completely saturated with tobacco juice a passage will be afforded

for smoke to the chamber C and thence thru the passage B² in the mouthpiece B.

The filtering material is held in a hole B³ said material being compressed in forcing the filter into said hole as illustrated.

The passage thru the mouthpiece B² terminates in a cone-shaped surface B⁴ formed on the inner end of the portion B¹, and the inner end of said passage, indicated by B⁵ is formed at an angle to the main passage B² as illustrated so that a pipe cleaner may be easily passed entirely thru the passage B² comprising the passage B⁵ in cleaning the said passage.

The inner end of the bore C is formed with a conical recess C² to freely guide the filter into the passage C¹ when the mouthpiece is inserted in the stem portion.

In smoking the pipe, the free end of the filter by reason of resting in the recess A⁴ does not absorb much if any tobacco juice and may therefore be grasped by the fingers to remove the filter from the mouthpiece without soiling the fingers.

In smoking, the smoke passes thru the mesh or interstices of the filtering material and thru the chamber C to the inlet B⁵ and thru passage B², the moisture in the smoke being absorbed by the filtering material, and any excess flowing into and being retained by the chamber C from which it may be readily cleaned.

It will be found that the portion of the filter F adjacent the end of the mouthpiece will be practically free from moisture, as the smoke after it leaves the passage C¹ flows to the inlet B⁵ without depositing much if any moisture in this portion of the filter so that the filter may be grasped at this point to remove it from the stem without soiling the fingers.

In this construction the outer form of the pipe is completely preserved.

The ordinary pipe cleaner sold by most tobacco dealers thruout the United States will serve as a filter. This cleaner is about seven inches in length and when cut into four equal portions, each portion may serve as a filter when the pipe is made as illustrated in the drawings.

Having thus described my invention I claim as new:

- 5 1. A pipe comprising a bowl and stem portion and a mouth piece portion removably secured to said stem portion, said stem portion and mouthpiece each having single passage formed therein, and a cylindrical rod-shaped, absorbent filter extending entirely thru said passage in the stem to a point below the bowl
10 and connected to the inner end of said mouthpiece in removable relation therewith and removable together with the mouthpiece from said stem portion, said construction embodying a chamber of enlarged diameter relative
15 to the diameter of the filtering material formed adjacent the inner end of said mouthpiece the passage in said stem extending beyond the passage leading from the bowl to provide a recess for the purpose set forth.
- 20 2. A pipe comprising a bowl and stem, having a single passage extending from below the bowl and thru said stem, a mouthpiece removably attached to said stem, said mouthpiece having a hole formed in its inner end of a less diameter than that of said filter, and a filter one end of which is held in said hole and extending therefrom thru said passage in the stem.
- 25 3. A pipe comprising a bowl and stem, having a single passage extending from the bowl and thru said stem, a mouthpiece removably attached to said stem, said mouthpiece having a hole formed in its inner end, and a filter one end of which is held in said hole and extending therefrom to said passage in the stem said stem having a chamber of enlarged diameter relative to the passage therein formed adjacent the inner end of the mouthpiece thru which smoke may flow in passing to the passage in the mouthpiece.
- 30 4. A pipe comprising a bowl and stem, a mouthpiece having a passage therethru and removably attached to said stem and having a hole formed in its inner end, said stem having a passage extending from below the bowl to said mouthpiece and reduced in diameter at the bowl end of the pipe and increased in diameter at its opposite end, a filter of absorbent material having one end compressed
35 and resting in said reduced portion of the passage and extending therethru into said hole in the mouthpiece and compressed and held by friction therein.
- 40 5. A pipe comprising a stem and bowl having a passage in open communication, a mouth-piece having a passage therethrough and removably attached to said stem, and having a hole formed in its inner end, said stem having a passage extending beyond the communicating passage formed in the bottom of the bowl, a filter comprising a wire with absorbent material thereon, one end of which is compressed and held by friction in said hole in the mouth piece and the other end of which

extends beyond the passage leading from the bowl to the passage in the stem.

In testimony whereof I have affixed my signature.

FRANK M. ASHLEY.
